A. E. HOLADAY,
PRESSURE ROLL RELEASE FOR CLOTHES WRINGERS,
APPLICATION FILED OCT. 26, 1916.

1,220,127.

Patented Mar. 20, 1917.

FIG. 1.

FIG. 2.

FIG. 3.

UNITED STATES PATENT OFFICE.

ALBERT E. HOLADAY, OF NAUGATUCK, CONNECTICUT, ASSIGNOR TO THE AMERICAN WRINGER COMPANY, OF WOONSOCKET, RHODE ISLAND, A CORPORATION OF RHODE ISLAND.

PRESSURE-ROLL RELEASE FOR CLOTHES-WRINGERS.

1,220,127.

Specification of Letters Patent. Patented Mar. 20, 1917.

Application filed October 26, 1916. Serial No. 127,893.

To all whom it may concern:

Be it known that I, ALBERT E. HOLADAY, a citizen of the United States, residing at Naugatuck, in the county of New Haven 5 and State of Connecticut, have invented certain new and useful Improvements in Pressure-Roll Releases for Clothes-Wringers, of which the following is a specification, reference being had therein to the accompanying 10 drawing.

This invention relates to a certain new and useful improvement in a pressure roll release for clothes wringers, and consists in providing a transversely breakable top bar 15 for the wringer frame with means for holding the abutting ends of the breakable bar in alinement in such a manner that it can be quickly released in order to allow the bar to break and move upwardly so as to release 20 the pressure.

Another object of my invention is to provide a pressure release which is exceedingly simple and cheap in construction and one in which a locking member employed for 25 holding the sections of the breakable bar in alinement is provided with oppositely disposed buttons for rocking the locking member on its pivot in order to release the breakable bar whereby the same can be operated from either side of the wringer.

Another object of my invention is to provide a pressure release in which the sections of the transversely breakable bar are connected together by a hinge, each section 35 having an upwardly projecting lug which is adapted to be engaged by a locking hook of a locking member pivotally carried by one of the sections in such a manner that when the locking member is rocked in either 40 direction, the locking hooks will be thrown out of engagement of the locking lugs to release the bar so as to allow the same to break transversely and move upwardly so that the pressure screws carried thereby will 45 be thrown toward each other in order to release the pressure.

Other and further objects and advantages of the invention will be hereinafter set forth and the novel features thereof defined by 50 the appended claims.

In the drawings,

Figure 1 is a side elevation of a clothes wringer partly in section showing the appli-

cation of my improved construction of pressure release, the breakable bar being shown 55 in dotted lines in raised position;

Fig. 2 is an enlarged longitudinal section through the breakable bar; and

Fig. 3 is a perspective view of a locking member for the sectional breakable bar. 60

Like numerals of reference refer to like parts in the several figures of the drawing.

In the drawing I have shown a wringer composed of a frame 1 having slotted side bars 2 in which are mounted pressure rolls 65 3 and 4 carried by suitable bearings, the upper bearings having spring supports 5 on which are mounted pressure springs 6 engaged by bearing plates 7 carried by a pressure bar 8. The construction thus far described is of an ordinary construction of clothes wringer and pressure means now in use.

Secured to the upper ends of the side bars 2 are caps 9 in the form of castings having 75 overhanging lips 10 extending over the slots of the side bars and under which are adapted to be arranged the ends of a sectional top bar 11 formed of two sections pivotally connected together by a hinge as shown 80 at 12 on the under side.

The ends of the sections of the top bar are rounded on their under sides, as clearly shown in Fig. 2, and the sections are provided with boxes 13 carrying pressure 85 screws 14 which are adapted to engage the bearing plates 7 on the pressure bar 8 so as to adjust the pressure on the pressure rolls.

One of the sections of the top bar 11 is provided with a locking member 15 pivotally mounted on the end sections between the abutting ends as shown at 16, said locking member having locking hooks 17 and 18 extending in opposite directions which are adapted to engage the upwardly projecting angled ends 19 of plates 20 secured on the top of the sections of the top bar, said angle ends being rounded as shown at 21 so that the hooks 17 and 18 can move off of the angled ends in order to allow the sectional top bar to break as shown in dotted lines in Fig. 1, as when the locking member 15 is rocked on its pivot 16, the locking hooks 17 and 18 are moved transversely out of engagement with the angled ends of the 105 plates 20. The locking member 15 is pref-

erable formed of a plate having a central upwardly disposed portion which is split vertically, the portions to each side of the split being bent outwardly and downwardly to form the hooks 17 and 18, and the upper edge of the plate at each end carries a push button 22 which can be readily struck by the operator so as to rock the locking member and release the sections of the top bar.

In operation, the ends of the top bar are forced under the overhanging lips of the caps 9, and the sections are forced together until brought into longitudinal alinement and by moving the locking member, the locking hooks 17 and 18 will engage the angled ends of the plates 20 and hold the sections in their proper position. The pressure screws are then adjusted so as to obtain the desired pressure on the pressure rolls through the medium of the pressure means, and the wringer is then in position to be operated in the ordinary manner.

In case a foreign object is drawn between the pressure rolls and it is desired to instantaneously release the pressure, the operator strikes one of the push buttons 22 which throws the locking hooks out of engagement with the plates and the upward pressure forces the top bar into the position as shown in dotted lines in Fig. 1 so as to release the pressure instantaneously.

I claim:

1. A clothes wringer, comprising a frame having pressure rolls and pressure means for said rolls mounted therein, a transversely breakable top bar mounted in said frame having means for adjusting said pressure means, a locking member carried by the end of one section of said top bar having oppositely disposed locking hooks and laterally projecting portions, and plates having upwardly projecting ends carried by the sections of said bar adapted to be engaged by the hooks of said locking member for holding said section in alinement.

2. A clothes wringer, comprising a frame having pressure rolls and pressure means for said rolls mounted therein, cap members carried by the side bars of said frame, a sectional top bar mounted in said frame under said cap members having means for adjusting said pressure means, a locking member pivotally mounted on the abutting end of one of the sections, and having oppositely disposed hooks, and plates carried by the abutting ends of the sections of said top bar having upwardly projecting end portions adapted to be engaged by said hooks for holding said top bar in position within said frame.

3. A clothes wringer, comprising a frame having pressure rolls and pressure means for said rolls mounted therein, cap members carried by the side bars of said frame at

their upper ends thereof, a top bar formed of two sections pivotally connected together mounted within said frame under said cap members the free ends of said top bar being rounded, pressure screws carried by said top bar for adjusting said pressure means, a pivoted locking member mounted on one of the abutting ends of said sectional top bar, push buttons carried by said locking members and extending outwardly therefrom to each side of said top bar, angled plates carried by the abutting ends of said top bar, and oppositely disposed hooks carried by said locking member adapted to engage the angled ends of said plates for holding the sections of said top bar in alinement with one another.

4. A clothes wringer, comprising a frame having pressure rolls and pressure means for said rolls mounted therein, cap members carried by the upper ends of the side bars of said frame, a top bar formed of two sections pivotally connected together mounted in said frame under said cap members, the free ends of said top bar being provided with rounded lower portions, threaded boxes carried by said top bar, pressure screws mounted in said threaded boxes for adjusting said pressure means, a transverse movable locking member mounted on the inner end of one of the sections of said top bar having oppositely disposed push buttons, angled plates carried by the inner ends of the sections of said top bar, and oppositely disposed hooks carried by said locking member engaging said plates for holding said sections in alinement with one another.

5. A clothes wringer, comprising a frame having pressure rolls and pressure means for said rolls mounted therein, cap members carried by the side bars of said frame at their upper ends, a transversely breakable top bar mounted in said frame formed of sections pivotally connected together, the free ends of said sections being arranged under said cap members, plates secured to the inner ends of the sections of said top bar having upwardly projecting members, and a transversely movable locking member mounted on the inner end of one of the sections of said top bar between the abutting ends thereof having oppositely disposed depending hook members engaging the upwardly projecting portions of said plates for holding said sections in alinement with one another, said locking member having oppositely disposed push buttons.

6. A clothes wringer, comprising a frame having pressure rolls and pressure means for said rolls mounted therein, a top bar formed of two sections pivotally connected together mounted on said frame, means for preventing the upward movement of said top bar, plates mounted on the inner ends of the sections of said top bar having upwardly pro-

jecting portions, a transversely movable locking member mounted on the inner end of one of said sections between the abutting ends thereof, said locking member having laterally extending push buttons arranged to each side of said top bar, and oppositely disposed hooks formed on said locking member engaging the upwardly projecting portions of said plates for holding said sections in locked position in respect to one another.

In testimony whereof I hereunto affix my signature.

ALBERT E. HOLADAY.
